TOILET PAPER DISPENSER

Hugh E. McCants, Dallas, Tex., assignor to
Reserv-A-Roll Company, Inc.

Application May 7, 1953, Serial No. 353,533

6 Claims. (Cl. 242—55.3)

This invention relates to article dispensing machines and more particularly to machines for dispensing toilet tissue in rolls.

The principal object of the invention is to discourage pilfering of toilet tissue from public rest rooms by transients and others, causing financial loss and inconvenience for those responsible for the maintenance of the rest rooms.

Another object of the invention is to provide an inexpensive but efficient toilet tissue dispenser which is designed to be either recessed in a wall or suspended thereon but in any case, is adapted to contain, in superimposed relationship, a plurality of rolls of toilet tissue, the lowest roll being the only one accessible to the user but which is locked against other than rotative movement for the dispensing of tissue. Not until the tissue is depleted from the roll spindle is it possible to remove the latter from the machine but in doing so, provision is made for automatic replacement of the depleted roll by a full roll.

Other objects will become manifest as the description proceeds, taken in connection with the accompanying drawing wherein:

Figure 1 is a front perspective view of a toilet tissue dispenser constructed according to the invention, with portions broken away.

Figure 2 is a view thereof in vertical section, showing a form of mounting in a wall recess, and

Figure 3 is a perspective view of a roll spindle, per se.

Continuing with a more detailed description of the drawing, reference numeral 10 denotes generally the casting or housing of the dispenser which includes the side walls 11, top 12 and bottom 13. While the housing may be affixed directly to a wall, it is preferred that it be partially concealed in a recess in the wall and the drawing so illustrates this manner of mounting. To this end, the housing 10 has top and bottom brackets 14 affixed to its walls 11 which provide means for securing thereof to timbers 15 and 16 of a room wall 17.

The housing 10 is elongated to accommodate any desired number of toilet tissue rolls 18, hence, the housing will be hereinafter referred to from time to time as the roll magazine. The rolls 18 are deposited one at a time into the magazine through an opening 19 at its top and which is closed by a door 20, hinged along one edge of the opening at 21.

Each roll of tissue 18 has a spindle 22, on each end of which is a pintle 23, receivable in a vertical channel 24 defined by relatively spaced, parallel rails 25, a pair of which are affixed to the inner surface of each side wall 11 of the magazine or housing 10. At the upper end of each channel 24 is arranged an inclined guide flange 26 which is instrumental in guiding the pintles 23 of the spindles 22 into their respective channels.

The filler opening 19 is defined by a frame 27 which actually supports the door 20 and which has a right angular flange 28 conforming to and telescoping into the opening 19. This flange has tabs 29, apertured to

2

receive screws 30, by which the frame 27 is held secure in the opening 19. A lock 31 is provided for the door 20 and a substantially triangular plate 32 is attached to the inner surface of the door and provided with a plurality of holes 33 to receive pintles 23 of empty rollers 22, thus to serve as a storage for such rollers as they are removed from the lower or discharge opening of the magazine.

The discharge opening 34 of the magazine is embraced by a frame 35 which is secured to the magazine by means of screws 36, passing through apertures 37 of the frame into threaded holes 38 in gussets 39, affixed to the magazine at the four corners of the discharge opening 34. The frame 35 has opposing recesses 40 to pass the pintles 23 of the rollers 22 as the empty ones are removed from the magazine.

Returning to the channels 24 it will be observed in Figure 2 that the lower end of each channel opens onto an inclined track 41. The lowest portions of these tracks 20 are nearest the discharge opening 34 and are shaped to form a recess 42 into which drop the pintles of rollers 22 as the tissue rolls move by gravity down the inclined tracks 41. A rail 43 is disposed above and in parallelism with each track 41 to preclude upward displacement of the roll from the tracks.

When the tissue roll is disposed with its spindle resting in the recesses 42, it is in operative and accessible position for dispensing. However, the tissue roll cannot be withdrawn bodily through the discharge opening due 30 primarily to the paper wound on the roll which is brought up against a cross-member 48 when effort is made to lift the roll vertically to raise its spindle in opposing vertical channels 45. Also, if the spindle is backed up by inward pressure on the tissue roll, the latter will engage 35 the next highest roll. Hence, until all of the paper has been removed from the spindle will it be possible to remove the latter from the machine to make way for an unused roll which takes its place in dispensing position automatically.

40 The track 41 is inclined toward the recess 42, as pointed out above, then extends vertically at 45, thence horizontally as at 46. To remove an empty spindle, it is lifted upwardly through the vertical portion 45 of the channel until the pintles 23 thereof are brought up against the deflected surface *a* of a cam plate 47, one of which is 45 affixed to each end of the cross-member 48 which extends horizontally across the discharge opening 34 at its top and is rotatable about pivots 49. The cam plates 47 are each movable in a slot *b* made jointly in the flanges 44 and 44a defining the top and rear sides of the horizontal and vertical tracks 46 and 45, respectively. The slots *b* are revealed between the parts of the flanges 44 and 44a shown in cross-section in Fig. 2. Each cam plate 47 has an inwardly extending arm 50 which is held 50 down by a coil spring 51, attached at one end to the arm and at its other end to a bracket 52 affixed to the inner face of the side wall 11 of the magazine. The free ends of the arms extend through slots 53 in the outer rails 25 of the channels 24 and into the channels in the path of pintles 23 of rollers 22. These arms thus intercept all but the first tissue roll entering the magazine. The first roll assumes its dispensing position and cannot be removed from the machine for reasons earlier pointed out and the succeeding rolls are prevented from moving downwardly, being blocked by the first roll and the restraining arms 50.

When the first roll of tissue is depleted, the next succeeding full roll is brought into position by grasping the empty roller 22 and moving it upward through the vertical passages 45 so that its pintles 23 will engage against the cam surfaces *a* of plates 47 with a force sufficient to overcome the resistance of springs 51 as well as the weight of

the rolls resting on the ends of arms 50. This upward pressure on the cam plates 47 will raise the arms 50 so that the pintles 23 of the rollers may pass, whereupon the next succeeding roll will move downward into dispensing position, during which the springs 51 will return the arms 50 into position blocking the next highest roll. Action of the springs 51, combined with the weight of the column of tissue rolls will cause return of the cam plates 47 to their original positions with a snap action tending to thrust the empty roller out of the machine, its pintles passing through slots 49 in opposite sides of the frame 35, previously mentioned.

It is evident from the foregoing that losses sustained by rest room owners because of pilfering of toilet tissues is reduced to a minimum and however small these losses may be, the annoyance occasioned by such pilfering is considerable but is also obviated by the invention.

Manifestly, the construction as shown and described is capable of some modification and such modification as may be construed to fall within the scope and meaning of the appended claims is also considered to be within the spirit and intent of the invention.

What is claimed is:

1. In a machine for dispensing toilet tissue from rolls, a vertical magazine containing a column of superimposed tissue rolls, said magazine having a lateral filler opening adjacent its top and a lateral discharge opening adjacent its bottom, guide channels on opposing walls of said magazine having open lower ends, a spindle for each tissue roll having pintles engaging in said channels, an inclined track onto which said pintles are deposited from the open lower ends of said channels for movement toward said discharge opening, said tracks each having a recess for intercepting said pintles to hold the lowermost of said rolls in dispensing position in relation to said discharge opening, a cross-member pivotally disposed above said discharge opening, a cam plate affixed to each end of said cross-member, each having an arm thereof extending operatively into one of said channels for sustaining all but the lowermost of said rolls, spring means holding the arms of said cam plates in operative position, opposed vertical and horizontal channels communicating with said track recesses for the rearward, upward and forward passage of empty spindles from said recesses said cam plate lying partially within said vertical and horizontal channels for engagement by the pintles of said empty spindles during their removal for displacing said arms to release another tissue roll for movement to dispensing position.

2. In a machine for dispensing toilet tissue from rolls, a vertical magazine adapted to contain a column of superimposed rolls of tissue, said magazine having a filler opening adjacent its top and a dispensing opening adjacent its bottom, a lockable closure for said filler opening, a spindle for each roll having pintles, vertical channels on opposed sides of said magazine communicating with said pintles, inclined tracks under said channels extending downwardly, upwardly and forwardly and having recesses at their lowest points for receiving and retaining said pintles to dispose a tissue roll in dispensing position in said dispensing opening, means to prohibit bodily removal of an undepleted tissue roll from dispensing position, a cross-member pivoted in said magazine above said dispensing opening, spring biased means affixed to each end of said cross-member and normally disposed in said channels to intercept pintles of the next highest roll in said magazine, the pintles of empty spindles being adapted for upward and forward displacement in said tracks for removal of said spindle from said magazine, said spring biased means being engaged and elevated by the pintles

of an empty spindle being removed from said recesses and tracks to release said next highest tissue roll for movement to dispensing position.

3. In a machine for dispensing toilet tissue from rolls, a vertical magazine adapted to contain a column of superimposed rolls of tissue, said magazine having a filler opening adjacent its top having a lockable closure and a dispensing opening adjacent its bottom, channels in opposed walls of said magazine, a spindle for each tissue roll having pintles movable in said channels, opposed and inclined tracks below said channels onto which said pintles are deposited, said tracks extending forwardly to define a recess adjacent the front of said magazine to dispose a tissue roll in dispensing position, said tracks further extending upwardly and forwardly for the upward and forward displacement of pintles of empty spindles during their removal from said cabinet, means for preventing removal of a roll of tissue from said dispensing position through said dispensing opening, a cam plate pivoted adjacent each channel having a first member normally sustaining said column of tissue rolls in said magazine and a second member engageable by the pintles of an empty spindle during its removal from said dispensing position to actuate said first member to dispose a full roll in said dispensing position.

4. In a machine for dispensing material from rolls, a vertical magazine adapted to contain a column of said rolls and having a filler opening adjacent its top and a dispensing opening adjacent its bottom, a lockable closure for said filler opening, a spindle for each roll having pintles, vertical channels on opposing walls of said magazine for receiving said pintles, tracks below said channels for advancing said rolls singly to dispensing position in said dispensing opening, means supporting the spindle of a roll in dispensing position, means precluding removal of a spindle from dispensing position until the roll is depleted therefrom, said tracks being disposed for upward and outward movement of the pintles of empty spindles, spring biased means pivotally mounted adjacent each of said channels, a first member integral with said spring biased means for sustaining said column of rolls while a roll is in dispensing position, a second member integral with said spring biased means engageable by the pintles of an empty spindle during its removal from said dispensing position to displace said roll sustaining means to release another roll for movement to said dispensing position.

5. The structure of claim 4 in which the roll column sustaining means consists of a plate having an arm spring biased to engage under the pinte of the spindle of the lowest roll in the column and provided with a cam surface against which the pintles of an empty spindle is engaged during the removal from the machine to dislodge said arm to release said lowest roll.

6. The structure of claim 4, said tracks each having a recess for the reception of the pinte of a spindle in roll dispensing position and a vertical and a horizontal channel in communication with said recess through which the pintles are passed to remove said spindle from said machine and to actuate said roll sustaining means.
